(57) **CLAIM**

We claim the ornamental design for a multi-function printer, as shown and described.

DESCRIPTION

FIG. 1 is a front perspective view of a multi-function printer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another left side view thereof, showing the multi-function printer in an alternate configuration.

The broken lines illustrating portions of the multi-function printer depict environmental subject matter and form no part of the claimed design.

The dot-dash broken lines define boundaries the between the claimed and non-claimed subject matter and form no part of the claimed design.
